(57) **CLAIM**

The ornamental design for a pet chew toy, as shown and described.

DESCRIPTION

FIG. 1 is a perspective view of a pet chew toy showing the design;

FIG. 2 is a first end elevation view of the pet chew toy shown in FIG. 1;

FIG. 3 is a second end elevation view of the pet chew toy shown in FIG. 1;

FIG. 4 is a top plan view of the pet chew toy shown in FIG. 1;

FIG. 5 is a bottom plan view of the pet chew toy shown in FIG. 1;

FIG. 6 is a first side elevation view of the pet chew toy shown in FIG. 1;

FIG. 7 is a second side elevation view of the pet chew toy shown in FIG. 1;

FIG. 8 is a cross-sectional view along 8-8 of the pet chew toy shown in FIG. 6;

FIG. 9 is a cross-sectional view along 9-9 of the pet chew toy shown in FIG. 6;

FIG. 10 is a cross-sectional view along 10-10 of the pet chew toy shown in FIG. 6; and,

FIG. 11 is a cross-sectional view along 11-11 of the pet chew toy shown in FIG. 6.

The broken lines shown in the figures represent portions of the pet chew toy that form no part of the claimed design. The pet chew toy is shown with a symbolic break in its length. The appearance of any portion of the article between the break lines forms no part of the claimed design.

1 Claim, 8 Drawing Sheets
